J. D. PEDERSEN.

RIFLE BARREL.

APPLICATION FILED JULY 14, 1917. RENEWED MAR. 22, 1919.

1,355,422.

Patented Oct. 12, 1920.

Inventor:
John D. Pedersen,
By his Atty, F. H. Richards.

UNITED STATES PATENT OFFICE.

JOHN D. PEDERSEN, OF JACKSON, WYOMING.

RIFLE-BARREL.

1,355,422.

Specification of Letters Patent. Patented Oct. 12, 1920.

Application filed July 14, 1917, Serial No. 180,492. Renewed March 22, 1919. Serial No. 284,516.

To all whom it may concern:

Be it known that I, JOHN D. PEDERSEN, a citizen of the United States, residing in Jackson, in the county of Lincoln and State 5 of Wyoming, have invented certain new and useful Improvements in Rifle-Barrels, of which the following is a specification.

This invention relates to rifle barrels, and a principal object is to furnish an improved 10 barrel especially adapted for use in rifled shoulder arms. A further object is to provide means whereby the work of finally shaping the projectile to conform to and engage with the rifling ribs and in the rifling 15 grooves, will be accomplished in successive stages or periods, so that said work will be carried out in the rearward portion of the barrel and also in a modulated and progressive manner.

20 As regards some features thereof, my present invention is in the nature of a modification of, and an improvement on the rifle barrel described in my copending application Serial No. 177,252, filed June 27, 1917; 25 some features, however, of the improved rifle barrel herein described are regarded as being within the description, and as being covered by certain of the claims of said prior application.

30 A particular purpose of the present invention is to furnish a rifled gun barrel especially adapted for using un-cased (or thinly cased or coated) projectiles,—such as bullets of lead or those of similar character,— 35 in a highly effective manner, and therefore to provide for propelling such projectiles, or bullets, with powder charges of relatively high power; also, to accomplish these results in connection with a firearm barrel,—such 40 for instance as the barrel of a military shoulder-arm,—in which the rifling is of a standard form and construction suitable for using encased projectiles of the usual elongated form. Further advantages and objects are 45 pointed out and explained in the course of the following description.

In the drawings accompanying and forming a part of this specification, Figure 1 50 is a side view,—principally in section, and with some parts broken away,—of a rifle barrel made in accordance with my present improvements, and of composite construc- 55

Fig. 2 is an end view, as seen from the left-hand in Fig. 1.

55 Figs. 3 and 4 are cross sections in lines X³ and X⁴, respectively, of Fig. 1; Figs. 3^a and 4^a are end views (on an enlarged scale) of a projectile at successive stages of the surface formation thereof, as effected by 60 the successive riflings shown in Figs. 3 and 4, respectively.

65 Fig. 5 is an enlarged detail view especially arranged for illustrating certain features of the rifling, as hereinafter more fully explained.

70 Fig. 6 is a view analogous to a portion of Fig. 1, for illustrating certain variations in the form or arrangement of successive portions of the rifling.

75 Similar reference characters designate like parts in all the views.

Referring to the drawings, B indicates a rifle barrel of ordinary character; it may have, in practice, any desired or suitable external size and form. To facilitate illustration, a large portion of the length is broken away at 20, in Fig. 1, so that the rearward portion of the barrel may be more fully shown and be drawn on a larger scale. In 80 practice, the barrel B,—which, for the purposes of this description, I designate as the main barrel,—evidently may have such size, length and proportions as may be suitable for the particular firearm of which this barrel is to form a part, and I have herein represented in an approximate manner such a barrel of the class common to military 85 shoulder arms. These barrels are now generally made with the bore thereof,—as E, 90 Fig. 1,—having a diameter of about three-tenths of one inch, but in practice this bore may be smaller or larger, as may be required by the size and character of the firearm.

95 The main barrel, B, may be provided with the usual form of helical rifling, either of uniform twist, or gain-twist, as may be desired; however, I prefer to use in this barrel the more common uniform twist. The number of the rifling ribs may vary, 100 three to six being within common practice, but I prefer, for general use, to have the barrel B provided with four ribs, as 5,—see Figs. 1, 4, 5 and 6. To aid clearness of 105 illustration, the usual depth of the rifling grooves, 5', (Fig. 4), (and, of course, the

height of the rifling ribs 5), has been somewhat exaggerated in the present drawing. Said depth of grooves and height of ribs are, of course, to be measured in a direction radial to the geometric axis of the barrel.

At the rearward end thereof, the barrel B, (Fig. 1), is shown at 10, externally reduced in size and threaded, by way of showing one ordinary way, whereby the barrel may be removably fixed in the usual receiver, or frame, (not shown) of a firearm, in a well-known manner. Also, said main barrel B is shown as being bored out, (to the lines 12, 12, Fig. 1), to form the usual cartridge chamber, suitable for the shell, or "powder-case," (not shown) of a high-power cartridge having a long-range projectile. Into said chamber 12, a secondary barrel, D, is shown closely fitted, thus forming a complete barrel having a composite construction. It should be understood, however, that in some instances, if desired, said portion or auxiliary barrel, D, may be made integral with the main barrel, B; in this case, of course, the barrel B will have no chamber 12 available for separate use, since the member D will not be removable. Such an integral form of the complete barrel is not shown herein, but has been illustrated in my aforesaid application Serial No. 177,252.

In the composite form of the barrel shown in Figs. 1, 2, 3 and 6, the member D is extended rearwardly of the member B, (Figs. 1, 2), and is there shown enlarged, as at 14, and provided with a cartridge chamber 15; this chamber should be of suitable size and proportions for receiving the cartridges which, in any given instance, are to be used in the composite barrel. Said chamber 15, in some instances if desired, may be of the same size and proportions as the chamber 12, but said composite form of the barrel is more especially intended for use with ammunition of two kinds, viz., for high-power, long-range cartridges when the member D is removed, and for a lower power and shorter range cartridge, when said member D is in place.

Thus in the complete barrel, this has a continuous bore which in a short length thereof, and adjacent to the chamber 12 in the rear end thereof, (as in the zone N from line V to line V', Fig. 1), is provided with relatively small rifling ribs for initially grooving a projectile, and which forward of said small ribs, (and forward of said zone N of the initial projectile-grooving action), is provided with rifling ribs arranged for changing the initial grooving of the projectile. A further feature is that said zone N of initial grooving, is extended forwardly from said chamber 15 to a length or point forward of the position when the gases nor-

mally will have reached their maximum pressure, so that the projectile will pass from the relatively small to the larger rifling ribs at a time when the gas-pressure is beginning to decrease; during this period,— 70 or "time-interval,"—it is believed that the velocity of the projectile will be most rapidly increasing. This increase, however, of velocity is supposed to disappear at or somewhat before the moment when the projectile 75 leaves the muzzle, at 21, Fig. 1, of the barrel B.

The auxiliary barrel-portion D,—or that part of the complete barrel comprised within the zone N,—is shown as having the bore 80 thereof of a diameter larger than the diameter of the bore of the main barrel, and is also shown provided with rifling ribs, as 7,—with intervening grooves 7';—which are not only smaller and more numerous than the 85 ribs 5 of the main barrel, but are also located farther from the geometric axis of the barrel. In practice, the number of the ribs 7 relative to the number of the ribs 5, may be varied, but I prefer to make said smaller 90 ribs about double the number of the larger ribs; such an arrangement is shown in Fig. 5, where the four large ribs 5 are shown used in combination with eight of the smaller ribs 7. This arrangement and construction 95 I have found by practical tests to be particularly effective in operation.

In Fig. 5 a further feature is illustrated, in that the outer circle, at 31, of the ribs 5 and grooves 5', of the main rifling, is also 100 substantially coincident with the inner circle of the ribs 7 and grooves 7' of the auxiliary rifling. Thus it may be said that the two series of ribs and grooves,—as seen in an end-view of the barrel,—occupy two concentric 105 annular zones, respectively, the ribs 7 being in the outer zone indicated by the circles at 31 and 32, and the ribs 5 being in the inner annular zone indicated by the circles at 30 and 31, Fig. 5. A pair of the small ribs 7 110 are also shown in Fig. 5 located in a symmetrical position circumferentially with relation to each one of the larger ribs 5, but in practice, this symmetry of arrangement, while regarded as preferable, may be omitted 115 in some instances. In this view, Fig. 5, of course the curvature, or spirality, of the ribs is disregarded.

In Fig. 1, the ribs 7 are indicated as extending forward close to the rearward ends 120 of the larger ribs 5, but it should be understood that in some instances if desired, a space, or un-ribbed zone, as 8', Fig. 6, may be located between said ribs. In this case, however, the two series of ribs 7 and 5 together form in effect a "continuous" rifling for the complete barrel. By its motion and great momentum acquired in traversing the zone N, the projectile will readily pass from the ribs 7 and over said zone 8' and continue 130

along the ribs 5, in the required manner. The special features here described in connection with Fig. 6, have the advantage of permitting the projectile to pass beyond, or 5 partially beyond the rifling 7 before engaging with the rifling 5. Thus the small projecting ribs (Fig. 3^a) raised on the projectile by the small rifling-ribs 7, may be reduced, or "ironed out" by the cylindrical surface of 10 the bore within the zone 8.

In the zone 2,—Figs. 1, 6,—the ribs 5 are shown tapered or reduced to a wedge-like form, thus providing for a gradual engagement of the projectile with said ribs, and 15 avoiding so sudden a shock or resistance as otherwise might occur; this tapering form of the rib-ends of the rifling 5, may, however, be omitted in some instances, whenever desired, and is not essential to the principal 20 features of my present invention.

The relative effects of the successive rifling ribs, 7 and 5, upon a projectile are approximately shown in Figs. 3^a and 4^a, which correspond with the inner outlines of the bore 25 of the barrel, in Figs. 3 and 4, respectively. Thus Fig. 3^a shows a cross-section of a projectile, J, as initially grooved,—as at 7^a,—by the ribs 7, Fig. 3, to form the initial ribs 7^b on the projectile. Similarly, Fig. 4^a 30 shows said projectile as having formed therein the new and larger grooves, 5^a, corresponding to the ribs, 5, of the barrel B, in Fig. 4; in this latter operation, the initially-formed ribs on the projectile,—Fig. 35 3^a,—are reduced and eliminated by a complete re-forming of the outer surface-portion of the projectile.

The slight resistance offered by the relatively small ribs 7 to the initial forward 40 movement of the projectile, permits this movement,—on the firing of a cartridge,—to begin at a time (at a moment) when the gas-pressure is still comparatively low, so that the space behind the projectile will be 45 materially enlarged during a very early stage of the combustion of the powder. Consequently, during that initial forward movement, the projectile will have not only a low velocity, but also, for the instant, a low degree 50 of acceleration, so that a minimum amount of power will be consumed during that moment in inaugurating the rotation of the projectile, and thereby permit a more rapid acceleration of the forward movement 55 under a given and relatively low gas-pressure. Thus the rapidly increasing forward movement while the projectile is subjected to the low rib-resistance, tends to correspondingly increase the gas-space before the 60 gas-pressure can rise to its maximum. As a result of this action, the curve by which the gas-pressure is usually represented in a well-known diagrammatic manner, will be materially modified in a way to show a delay,— 65 as compared with the hitherto accepted prac-

tice,—of the moment when the gas will attain maximum pressure; this normally operates to reduce the maximum strain upon the barrel due to the burning therein of a given quantity of powder behind a projectile of a 70 given weight, and also,—within a given limit of that strain,—provides for burning a relatively larger quantity of powder behind a projectile of a given weight.

By reason of the modulation, as above explained, of the forces and pressures, the torsional strain on the initial rifling (and especially during the first one or two inches of said forward movement of the projectile), is believed to be materially less than normally 80 occurring with the usual style of rifling which has ribs of uniform cross-section dimensions throughout the length of the barrel. Hence my present improvements are especially applicable to rifled firearms having barrels of composite construction, and in which a main barrel is adapted for using high-power cartridges and is also, for some uses, provided with "an adapter," the bore of which forms a rearward extension of the 85 bore of the main barrel; one arm of this class,—a military shoulder-arm,—is described in my application filed April 28th, 1917, Serial No. 165,171, to which reference may be had.

In practice, by the time when the projectile has reached the forward end of the initial ribs 7, and thus come to the larger rifling ribs 5, the projectile has acquired such a velocity and momentum that it will "take" 100 the rifling of the main barrel without difficulty. As a result, therefore, of the said features and mode of action, when the barrel is provided with the relatively thin adapter-extension or supplemental barrel, as herein 105 shown, this is so far protected and relieved of the otherwise heavy strain, as to be reliable and effective under the severe conditions of continued service. Thus, also, I avoid the highly destructive action upon the projectile, which occurs when the bore of the adapter-barrel is a smooth-bore (not herein shown); that construction, as I have found by extended trials, allows the projectile to initially advance too rapidly, so that on 110 striking the rifling ribs of the main barrel,—and being then without rotation,—the projectile will often be so cut and deformed as to be practically destroyed before leaving the barrel.

In practice, the small-ribs zone, as N, may usually have a length which is somewhat greater than that of the well-known rising-pressure zone of a pressure-diagram for the cartridges proper for use in the barrel B, so 125 that,—as herein explained,—the increased resistance due to the projectile encountering the larger ribs 5, will be delayed, and so will not occur until after the gas-pressure has begun to reduce. The minimum length of the 130

zone N may be regarded as equal to about two and one-half times the diameter of the bore E, while a normal and preferable range thereof may be between four and ten diameters or calibers, according to size of bore, the twist of the rifling, and the character and power of the cartridges to be used; all these matters or factors are readily ascertainable by trial in any particular instance.

10 The breaking of the surface of the bullet into small undulations by the action of the rifling ribs 7, serves to prepare the bullet for the second and larger change of form which is effected by the main rifling 5. Thus 15 it may be said that the rotation of the bullet is effected first by means of a temporary, and preliminary formation thereof, and is then continued by means of a second and different formation thereof. The rotation is 20 inaugurated by the auxiliary rifling 7, acting upon the small ribs, as 7^a, of the bullet J,—as indicated in Fig. 3^a,—and the rotation is accelerated and continued by the main rifling, 5, acting upon the larger ribs, 7^b, (Fig. 4^a), which are formed on the bullet 25 after said preliminary formation thereof has been obliterated. Thus the initial grooving of the projectile is normally followed by the re-grooving thereof, and this is accompanied 30 by a reduction of the outside diameter,—and sometimes by a slight elongation,—as now will be readily understood by a comparison of the several circles at 30, 31 and 32; and of 35 Figs. 3 to 5, inclusive. In some instances, if desired, especially in firearm barrels of larger bore,—the inner circle of the initial grooving may be slightly smaller than the outer circle of the final grooving of the bullet; however, I deem it to be desirable that in 40 the initial grooving operation, the ribs 7 shall not cut so deeply into the bullet but that the final grooving operation will fully smooth out, or "seal," the initially-formed 45 ribs and grooves of the bullet. When these operations are properly carried out, the symmetrical arrangement of the ribs 7 and 5,—as already described in connection with Fig. 5,—becomes relatively unimportant, so that the member D may in practice be turned 50 to have any desired position relative to and within the member B.

Having thus described my invention, I claim:

1. A rifle barrel having in the rear end 55 thereof a cartridge chamber, and having a bore which in a zone thereof adjoining said chamber is provided with a series of rifling ribs arranged for initially grooving a projectile with one number of grooves, and 60 which forward of said initially-grooving ribs is provided with another series of rifling ribs that are in position and adapted for first obliterating the initial grooving and for then re-grooving the projectile with a 65 different grooving.

2. A rifle barrel having in the rear end thereof a cartridge chamber, and having a bore which in a zone thereof adjoining said chamber is provided with a series of initial rifling ribs arranged for initially grooving a 70 projectile with one number of grooves, and which forward of said initially-grooving ribs is provided with rifling ribs of a number less than the number of said initial rifling ribs, and that are in position and 75 adapted for first obliterating the initial grooving and for then re-grooving the projectile with a different grooving.

3. A rifle barrel having a cartridge chamber, and having forwardly from said chamber a bore which in a zone thereof adjacent to said chamber is provided with a relatively numerous series of rifling ribs for initially forming on the projectile a numerous series of relatively small ribs and 85 grooves, and which forward of said zone is provided with a different and less numerous series of rifling ribs arranged for forming on the projectile a different and less numerous series of relatively larger ribs and 90 grooves.

4. A rifle barrel having a cartridge chamber, and having forwardly from said chamber a bore which in a zone thereof adjoining said chamber is provided with a series of 95 rifling ribs for initially grooving a projectile with one number of grooves, and which forward of said zone is provided with rifling ribs that are in position and arranged for re-grooving the projectile with a different 100 number of different grooves, the rifling ribs in said zone having the inner circle thereof of a diameter larger than the diameter of the inner circle of said re-grooving rifling ribs.

5. A rifle barrel having a cartridge chamber, and having forwardly from said chamber a bore which in a zone thereof adjoining said chamber is provided with a series of relatively small rifling ribs for initially 110 grooving a projectile, and which forward of said zone is provided with a series of larger rifling ribs that are in position and arranged for re-grooving the projectile with a different series of grooves, said series of 115 smaller rifling ribs having the inner circle thereof of a diameter larger than the diameter of the inner circle of said series of larger rifling ribs.

6. A rifle barrel having a cartridge chamber, and having a bore which in a zone thereof adjoining said chamber is provided with relatively small and numerous rifling ribs arranged for initially grooving a projectile, and which forward of said small 120 ribs is provided with larger and less numerous rifling ribs that are in position and adapted for obliterating said initial grooving and for then re-grooving the projectile.

7. A rifle barrel having a cartridge chamber, and having a bore which in a zone thereof adjoining said chamber is provided with a series of relatively small and numerous rifling ribs arranged for initially grooving a projectile, and which forward of said small ribs is provided with a series of larger and less numerous rifling ribs that are in position and adapted for obliterating said initial grooving and for then re-grooving the projectile, said series of the smaller rifling ribs having the inner circle thereof of a diameter larger than the diameter of the inner circle of said series of the larger rifling ribs.
8. A rifle barrel of composite construction and having a continuous bore, and comprising a main barrel having at the rear end thereof a short secondary barrel provided with a cartridge chamber, and adjacent to said chamber provided with a series of relatively small rifling ribs for initially grooving a projectile with one number of grooves, said main barrel at a distance forward of said small ribs being provided with a dif-

ferent series of relatively larger rifling ribs that are in position and adapted to re-groove the projectile with a different grooving.

9. The herein-described improvement in composite rifle barrels, it comprising a main barrel having in the bore thereof a series of rifling ribs, and having a cartridge chamber in the rearward end thereof, in combination with a secondary barrel having the forward end thereof removably inclosed in said cartridge chamber of the main barrel, and having in the rearward end thereof and rearward of the main barrel a cartridge chamber and in the bore thereof having a series of rifling ribs for initially grooving a projectile with one number of grooves, said main barrel having the bore thereof of a diameter smaller than the diameter of the bore of the secondary barrel.
